(57) **CLAIM**

The ornamental design for a wheel rim as shown and described.

DESCRIPTION

FIG. 1 is a right-oriented perspective view of a wheel rim according to my new design;

FIG. 2 is a left-oriented perspective view thereof;

FIG. 3 is a front elevation view thereof;

FIG. 4 is a right side elevation view, the left side elevation view being a mirror image thereof; and,

FIG. 5 is a top plan view, the bottom plan view being a mirror image thereof.

The broken lines in the figures are included for the purpose of illustrating portions of a wheel and form no part of the claimed design.
